GOLF TRAINING AND RECORDING APPARATUS

Robert Crowley, North Quincy, Mass.

Application May 13, 1947; Serial No. 747,736

3. Claims. (Cl. 273—35)

1

My present invention is a novel and efficient golf training apparatus and is an improvement over the devices illustrated and described in my prior Patents Nos. 2,150,530 and 2,169,407.

Important objects of the present invention are to simplify and improve my said prior devices by presenting more practical and expeditious adjusting arrangements and by the addition of more complete gauging apparatus, whereby every detail of the stance and hitting are of a golf player may be recorded for purposes of instruction, practice, and reference.

I have discovered from many years of study as a golf professional that almost every golfer when addressing a ball shows a slight and individual variation as to stance which is generally accepted to include the actual position of the feet, the distance from the feet to the ball, and the position of the ball laterally in relation to the feet. And, of course, as is well known, a proper stance is a necessary requisite for any player desiring to become proficient in golf, and, further, will assist greatly in enabling an expert player to obtain the best results.

Also from my tests I have found that the prime difficulty in acquiring a proper stance arises not from determining the most efficient position for each player, but from being able to remember such position and repeatedly duplicate the same. This is most important in golf, as even the variation of a fraction of an inch in the width of the space between the feet, or of the distance from the feet to the ball, or of the forward or backward position of the ball in relation to the feet, will oftentimes cause a substantial margin of error in a player's resulting stroke.

It is, therefore, most desirable to be able to determine the proper stance and also to be able to record the same quickly and accurately for further reference. Thus, by employing my novel apparatus I may accomplish such dual result, thereby effecting a valuable saving in time for an instructor in not having to repeatedly reposition his pupil—for a practitioner and an expert in not having to practice or experiment with an improper stance when checking his game.

It is further well settled in golf that the most successful method of hitting the golf ball, particularly on shots where a substantial amount of distance is required, is to have the club-head approach the ball in an arc slightly from the "inside-out" and thence straight thru the ball on the desired line of flight. In putting and in playing short approach or chip shots, however, it is preferably to keep the club-head parallel to the line of flight, and I have therefore designed my novel training, instruction, and recording apparatus with adjustable guiding means so that at all times a player may have a proper directional indication for the club-head whether

driving, playing full wood or iron shots, pitching, chipping or putting.

In carrying out my invention I provide a plurality of universally interlocking, adjustable, and maneuverable guides provided with measuring indices for recording every individual detail of a golf player's stance, and manually operable means such as set-screws, or the like, to lock the guides when in desired adjustment; and in addition I provide a ball-hitting area readily adjustable to act as a directional aid for the club-head on both the back and down swing for every type of shot.

Referring to the drawings illustrating a preferred embodiment of my invention:

Fig. 1 is a plan view of my apparatus;

Fig. 2 is an enlarged view partly in cross-section on the line 2—2 of Fig. 1, looking in the direction of the arrows;

Fig. 3 is an enlarged partial plan view showing the ball-measuring quadrant;

Fig. 4 is a view partly in cross-section on the line 4—4 of Fig. 1, looking in the direction of the arrows; and

Fig. 5 is an enlarged perspective view, partly broken away, showing the foot-adjusting quadrant construction.

Referring to the drawings, 1 and 2 designate two substantially parallel bars, preferably rectangular in shape and made of wood, plastic, metal, or the like, and spaced apart to provide a hitting area thru which the clubhead may travel to strike a ball 3. One end of said strip 2 is slightly curved, as at 4, the degree of said curve being predetermined as suggestive of the most effective path for the clubhead to follow as it approaches the ball 3.

Connecting said bars 1 and 2 near each end thereof and thru suitable openings therein are identical rods 5—5, each of which rods are formed with threads on one end to receive a stop nut 6 to support the bar 1 and a knurled thumb nut 7 to cooperate with said nut 6 in locking and retaining said bar 1 in fixed position. The bar 2 is adapted to slide on said rods 5—5 and to be adjustably secured at any desired distance from the bar 1, and is thus provided with suitably tapped openings on its top surface to receive correspondingly threaded knurled thumb screws 8—8 to impinge against the rods 5—5 where desired, for locking engagement therewith.

Centrally of the bar 2 and secured thereto by any suitable means, such as a pair of small screws 9 and corresponding nuts 10, is the attaching flange 11 of a plate 12, the rearwardly extending portion of which plate 12 carries a swinging quadrant 14 which, in turn, is rigidly connected to one end of a longitudinal rule gauge 15 by spaced rivets 16 and 17. Entering corresponding openings thru said plate 12, said quadrant 14 and

said gauge 15 between said rivets 16 and 17 is a screw 18 provided with an adjusting thumb nut 19.

Mounted on a screw 21 housed near the extremity of said gauge 15 is a pivot block 20 formed with a diametrical opening therethru to receive in hinged association a measuring frame 22 universally movable, and having cooperating therewith a ball-locating slide 22 comprising a cross member 23 and depending slide members 24-24 adapted to frictionally engage the sides of said frame 22 and thus remain in desired position during measuring and recording use.

The upper surface of the plate 12 is marked accurately with a centre line 25 to be used as a guide for the zero mark on the degree markings 26 etched on the quadrant 14. With this measuring arrangement, it is thus possible for an instructor or a player to determine the exact distance of the ball 3 from the end of the rule gauge 15 and also the number of degrees to the left or right of the centre line that the ball is positioned.

Slidably mounted on said gauge 15 is a rectangular tube 28 carrying a swinging quadrant 29, similar to 14 already described, and of greater width than said tube 28, which quadrant 29 may be locked in adjusted position to said tube 28 by turning a thumb nut 30. Said tube 28 is also marked with a centre line 31 to serve as a guide for lining up the zero mark on degree markings 32 suitably etched on the front end of the quadrant 29. Drilled at the opposite end of said quadrant 29 and adjacent the overhanging edges thereof are a pair of holes to receive the ends of bolts 34-34, secured by nuts 33-33, the heads of which bolts 34-34 carry a cross tube 35 extending transversely below the vertical tube 28, the shanks of said bolts 34-34 between said quadrant 29 and said cross-tube 35 being fitted with spacers 36-36 to retain the assembly in desired spaced relation.

In the cross-tube 35 slides a transverse rule-gauge 37 which cooperates with a shorter lateral rule gauge 38 and the longitudinal gauge 15 to define the position of a player's feet when addressing the ball 3.

Said gauges 37 and 38 are pivotally connected by a novel telescoping arrangement comprising sleeves 39 and 40, and rods 41 and 42, said sleeve 39 and rod 41 being pivotally fixed at 43 and 44, respectively, to said gauges 38 and 37; whereas said sleeves 40 and rod 42 are adjustably joined to said gauges 38 and 37 by a pair of stirrups 45 and 46, respectively, which stirrups may be locked in proper adjusted position by a pair of thumb nuts 47 and 48.

With my simple and quickly adjustable feet-positioning section, it is thus possible for an instructor to effectively service players with widely differing stances, to accurately record same for future reference and, if desired, to also utilize the cross-gauges 37 and 38 as directional guides parallel to the line of flight.

In utilizing my apparatus as an instruction medium for beginners, I first adjust the bar 2 so that it extends parallel to the bar 1 and sufficiently spaced therefrom to provide an adequate hitting area, and then line up the zero marks on the quadrants 14 and 29 with the centre lines 25 and 31, respectively, on the plate 12 and the tube 28 so that the longitudinal rule-gauge 15 is positioned precisely at right angles to the bar 2, said gauge 15 approximating the line of a club shaft when addressing the ball 3.

I then set the cross-gauges 37 at right angles to the gauge 15 and parallel to the bars 1 and 2,

and adjust the telescoping connectors angularly and suitably spaced to represent the player's proper feet location, preferably as shown in Fig. 1, with the sleeve 39 closer to the center line gauge 15 than the sleeve 40, and with the gauge 38 substantially parallel to the gauge 37, although the gauge 38 will be angularly positioned for each different type of shot.

I now have my pupil straddle the gauge 15 with his feet positioned within and at the angles indicated by the sleeves 39 and 40, and after sliding the tube forwardly or backwardly on the gauge 15 until the player's club head rests midway between the bars 1 and 2, I place the ball 3 centrally and in front of the club face, which, of course, in this instance would be slightly to the left of the frame 22, when straight-away extended. Thus positioned, the new player is properly stanced and in readiness to receive instruction in the swing and a preferred method of hitting the ball, in the teaching of which I find that the directional relation of the bars 1 and 2, and particularly the curved end 4 of the bar 2, serve as excellent guides for developing a correct manner of starting the clubhead on the back swing, of illustrating a proper arc for the clubhead to follow as it approaches the ball, and of providing a directional ally for the follow-through.

In adapting my apparatus to the expert player, I have discovered that it is invaluable as a source of reference. When the experienced golfer is at the peak of his game, I direct him to take his stance with the club addressing the ball and then proceed to quickly assemble my device about him, recording the exact measurements of each detail of such stance, as indicated by the figures on each of the rule gauges 15, 37, and 38, and the degree markings 26 and 32 on the quadrants 14 and 29, respectively.

The measurements shown on the cross-gauges 37 and 38 where the stirrups 45 and 46 are attached thereto will reproduce the angle and location of each foot and in cooperation with the free end of the gauge 15 will determine the position of each foot laterally in relation to the ball 3. The distance from the feet to the ball will be measured on the gauge 15 where it crosses the gauge 37 plus the distance from the end of said gauge 15 to the ball 3 determined by swinging the frame 22 and sliding the cross-member 23 over the ball, and as thus assembled swinging the frame back again for measuring on the rule-gauge 15.

With reference to the proposed line of flight, the exact angle of the club from the grip to the ball 3 will be obtained from the degree markings 32 on the quadrant 29 in relation to the centre line 31 on the tube 28. Similarly the number of degrees to the left or right of centre that the ball is positioned may be recorded from the degree markings 26 on the quadrant 14 in relation to the centre line 25 on the plate 12. By thus recording such measurements when a player is at the top of his game, I obtain valuable data which is readily available when this same player is playing poorly, and needs assistance, as I can quickly assemble my apparatus as per his chart, which enables him to automatically assume his most efficient stance, and assists him in getting back on his game at once.

When using my invention as a practice device, I find that the universal adjustability of all the parts, the speed of assembly and ready detachability of each section, and the simplicity and accuracy of the measuring media are all vital fac-

tors in helping a golfer with each type of shot and in mastering each club from the putter to the driver.

In utilizing my device for putting practice, I prefer to employ a skeleton assembly comprising the bars 1 and 2 connected at their right ends by the rod 5 as above explained but at the opposite ends by a wicket 50, the depending sides of which fit into suitable openings 49-49. Thus positioned, the bars 1 and 2 present a narrow alley with an open end to permit passage of a ball therethru and also serve as excellent guides for the putting stroke, and may be conveniently set up indoors or on a practice putting green.

In adapting my device to the practice of chip and short approach shots, I employ a similar skeleton set-up as for putting but with the exception that I replace the wicket 50 with the alternate bar assembly 5, 6, 7, and 8, preferably having the bars 1 and 2 spaced farther apart, but again stressing the parallel feature of said bars 1 and 2 as a directional aid for both the back swing, the hit and the follow-thru.

For practicing the longer shots—that is iron and wooden club shots requiring a full swing—I can, of course, utilize my chipping assembly to advantage, if desired, but generally I find it advisable to set up the complete apparatus, which is readily accomplished by sliding the fore end of the longitudinal gauge 15 with its accompanying quadrant 14 and ball measuring frame 22 thru the tube 28 and attaching such gauge assembly to the plate 12 on the bar 2 by means of the screw 18 and nut 19; then sliding the free end of the cross-gauge 37 thru the tube 35 and completing the assembly by connecting the rear cross-gauge 38 with its pivoted sleeve 39 telescoping with the rod 41 on said gauge 37 and the stirrups 46 and 45 fitted on the opposite ends of the gauges 37 and 38, respectively, with pivoted sleeve 40 likewise telescoping with pivoted rod 42. Thus set up, the practitioner can easily and quickly adjust the apparatus or any part thereof in experimenting with differing stances and swings until he finds those that produce the best results. Then, of course, he can note all pertinent measurements recorded during his most favorable playing for future reference.

It will be appreciated from the drawings that my apparatus, as shown, is adapted for use by right-handed playing golfers, but it is so constructed that by upsetting the bar 2 so that the curved end is at the opposite end, and also upsetting the cross-gauges 37 and 38 (provided with rule markings on each side) it can be used by left-handed players.

It will thus be seen that I have provided in an extremely simple, inexpensive, and efficient construction a novel and improved golf training and recording apparatus, universally adjustable for use by all golfers with whatever type of stance and swing, and particularly adapted for golf professionals in their instruction of the proper stance and swing, for experts as a reference medium, and for practicers of every type of shot from the drive to the putt.

In Fig. 1 I have shown in dotted lines the imprints of a player's foot illustrating several positions in which such feet may be measured. As long as the toe or heel, or both, of either or both feet are in contact with either or both of the

cross-gauges 37 and 38, and are also longitudinally positioned against either the inside or the outside of one of the sleeves 39 or 40, a player's feet location may readily be recorded and cataloged for the purpose of reference and instruction, so that in the future any desired foot position may be reproduced.

I claim:

1. A golf training and recording apparatus of the kind described, comprising clubhead swing-guiding means and adjustable stance-locating means, means perpendicular to said swing-guiding means and adjustably connecting therewith said stance-locating means, ball-position indicating means universally pivoted on said perpendicular means, in combination with measuring means to measure the position of each foot of a player, the distance and angle from each foot to a ball to be struck, the location of each foot

15 relatively to the other foot and to the perpendicular means, and the location of said ball in relation to said perpendicular means.

2. A golf training and recording apparatus of the kind described, comprising a pair of adjustable substantially parallel swing guide bars spaced

25 to receive a golf ball therebetween, means on one of said guide bars to detachably secure a longitudinal rule gauge perpendicular to said bars, means slidably on said rule gauge adapted to

30 slidably receive a cross rule gauge, a second cross rule gauge, and telescoping means connecting said cross gauges pivotally adjustable to simulate and reproduce the angular feet location of a player, and measuring means on said gauges whereby

35 vital details of any golfer's stance may be accurately recorded.

3. A golf training, practicing, and recording apparatus comprising a pair of adjustable and substantially parallel swing-guiding bars to be

40 positioned lengthwise in the direction of the line of flight of a golf ball to be struck by a club-head, one end of said inner bar curved to represent a preferred hitting arc for said clubhead, a pair of rods adjacent each end of said bars and adjust-

45 able connections between said rods and said bars permitting variation in spacing the bars, fixed means on said inner bar to detachably secure one end of a longitudinal gauge perpendicular to

50 said bars, a universally pivoted ball-locating member mounted adjacent said end of the gauge, means adjustably slidable on said gauge and carrying cross-means to slidably receive a trans-

55 verse gauge, a shorter transverse gauge crossing said longitudinal gauge adjacent the free end thereof, adjustable telescoping means connecting both of said transverse gauges whereby the feet

60 location of a player may be simulated, and measuring means on said gauges and on quadrants carried by said gauges to accurately determine the position of the player relatively to the location and the intended line of flight of the ball.

ROBERT CROWLEY.
